(57) **CLAIM**

The ornamental design for a drip chamber cap, as shown and described.

DESCRIPTION

FIG. 1 is a top perspective view of a drip chamber cap in accordance with the subject disclosure.

FIG. 2 is a front view thereof.

FIG. 3 is a back view thereof.

FIG. 4 is a right side view thereof.

FIG. 5 is a left side view thereof.

FIG. 6 is a top view thereof.

FIG. 7 is a bottom view thereof; and,

FIG. 8 is a side perspective view of the drip chamber cap attached to a drip chamber.

The elements depicted in broken lines in the various figures are included for environmental purposes only, and form no part of the claimed design.
